Primary Examiner—T. Chase Nelson*Assistant Examiner*—Karen Acker(74) *Attorney, Agent, or Firm*—Stiennon & Stiennon(57) **CLAIM**

The ornamental design for a ballistic body armor plate, as shown and described.

DESCRIPTION

FIG. 1 is a top plan view of the ballistic body armor plate of this invention;

FIG. 2 is a front elevational view thereof;

FIG. 3 is a left side view thereof, the right side view being a mirror image thereof;

FIG. 4 is a rear elevational view thereof; and,

FIG. 5 is a bottom plan view thereof.
